US0D1105933S

(12) **United States Design Patent** (10) **Patent No.:** **US D1,105,933 S**
(45) **Date of Patent:** **** Dec. 16, 2025**

(54) **CARTON**

(71) Applicant: **The Procter & Gamble Company**,
Cincinnati, OH (US)

(72) Inventor: **Ian Oliver Malott**, Hyde Park, OH
(US)

(73) Assignee: **The Procter & Gamble Company**,
Cincinnati, OH (US)

(**) Term: **15 Years**

(21) Appl. No.: **29/885,157**

(22) Filed: **Feb. 21, 2023**

Related U.S. Application Data

(62) Division of application No. 29/688,004, filed on Apr.
17, 2019, now Pat. No. Des. 981,846.

(51) **LOC (15) Cl.** **09-03**

(52) **U.S. Cl.**
USPC **D9/432; D9/737**

CLAIM

The ornamental design for a carton as shown and described.

DESCRIPTION

FIG. 1 is a perspective view of an embodiment of the carton;
FIG. 2 is a top view of the carton of FIG. 1;
FIG. 3 is a front view of the carton of FIG. 1;
FIG. 4 is bottom view of the carton of FIG. 1, opposite the
top view of FIG. 2;

FIG. 5 is a rear view of the carton on FIG. 1, opposite the
front view of FIG. 3;

FIG. 6 is a side view of the carton of FIG. 1; and,
FIG. 7 is a side view of the carton of FIG. 1, opposite the
side view of FIG. 6.

The dashed broken lines represent unclaimed structure or
features that form no part of the claimed design.

The dot-dash broken lines represent boundaries of the
claimed design; the dot-dash broken lines themselves form
no part of the claimed design.

1 Claim, 4 Drawing Sheets
